UNITED STATES PATENT OFFICE.

WILLIAM JOHN WHITING, OF HANDSWORTH, NEAR BIRMINGHAM,
ENGLAND.

REVOLVER-FIREARM.

SPECIFICATION forming part of Letters Patent No. 700,592, dated May 20, 1902.

Application filed May 27, 1901. Serial No. 62,106. (No model.)

To all whom it may concern:

Be it known that I, WILLIAM JOHN WHITING, works-manager, a subject of the King of Great Britain, residing at Douglas road, 5 Handsworth, near Birmingham, England, have invented certain new and useful Improvements in Revolver-Firearms, of which the following is a specification.

This invention relates to small-arms of the breakdown-revolver type; and the principal object is to provide such firearms with a simple and efficient form of cylinder-locking device in combination with means for retaining the cylinder with one of its chambers in alignment with the barrel and hammer when the revolver is opened. As applied to a certain type of automatic revolvers provision is also made for insuring the rotation of the cylinder in the proper direction when being fired. 10 In conjunction with the various locking devices means are provided for simultaneously disengaging the same from the cylinder, consisting of a push-piece working through the barrel-strap, hereinafter fully described, and 15 represented in the accompanying drawings, in which the application of the invention to automatic revolvers of the Webley-Fosbery type is represented in Figures 1 to 5, while Figs. 6 to 11 show its application to an ordinary revolver.

Fig. 1 is an elevation of the revolver closed, with a part in longitudinal vertical section to show the disposition of the alignment, direction, and locking studs, and the push-piece by which they are disengaged from the cylinder when it is required to dismount the latter. This view represents the direction and locking stud in engagement with a notch-cylinder, while the alignment-stud is raised clear 35 of the said cylinder. Fig. 2 is a similar view to Fig. 1, but with the revolver opened and the cylinder held in alignment with the barrel and hammer by the stud engaging in one of the rearward channel extensions of the zig-zag race. Fig. 3 represents a cross-section of the cylinder and extension-rib upon the dotted line x , Fig. 2. Fig. 4 is an under side plan of the extension-ribs, showing the disposition of the two studs and the jointed arms on which 45 they are mounted. Fig. 5 is a view showing, upon an enlarged scale, the arrangement of

the alignment, direction, and locking studs, with their arms, springs, and push-pieces in the positions they normally assume when the revolver is opened. Fig. 6 represents, partly in elevation and partly in longitudinal section, a revolver. Fig. 7 is a similar view to Fig. 6, but shows the revolver opened and the cylinder locked both against longitudinal movement for preventing the withdrawal of the same from off its axis and also against rotation to insure that one of its chambers shall remain in alignment with the barrel so long as the weapon is opened. Fig. 8 is a cross-section of the cylinder and top strap upon the dotted line x' , Fig. 7; and Fig. 9 is another cross-section of the same view, but taken through the front of the cylinder on the dotted line x^2 . Fig. 10 represents an underside plan of the barrel-strap, showing the arrangement of the locking device fitted therein. Fig. 11 represents, upon an enlarged scale and partly in elevation and partly in longitudinal vertical section, a part of the said revolver, showing the cylinder-locking device in the position it is made to assume when the weapon is closed, so as to leave the cylinder free for rotation.

In the automatic revolver represented in Figs. 1 to 5, the rotation of the cylinder by a zigzag race being constrained to work over a fixed peg on the bed or body of the revolver when the said cylinder is forced backward by the action of recoil after a discharge, a is the cylinder; a' , the flat-bottomed zigzag race thereof; b , the barrel-strap of the barrel b' ; c , the standing breech, and i the fixed peg on the frame for rotating the cylinder when the latter travels back under the recoil.

The alignment device direction-studs used in conjunction with the cylinder-rotating mechanism are arranged within a clearance or sinking b^4 in the under side of the barrel-strap, and the studs o and p are carried, respectively, by a pair of arms or levers $o' p'$, whose inner ends which overlap are jointed by or turn upon a common center-pin q , crossing the clearance b^4 , while suitable springs o^2 p^2 are provided between the top of the clearance and the levers for depressing both limbs for taking the studs into their engaging positions when the weapon is opened. A small

pusher r works through the top of the barrel-strap, and its inner end r' impinges in common upon the overlapping extensions of the two arms, the arrangement being such that when 5 the pusher is depressed the arms are rocked and the studs o and p are respectively lifted clear of their engagements with the cylinder, which may then be dismounted or withdrawn from its support.

10 The tip end o^3 of the arm o' , which carries the alinement-stud o , extends into the eye b^3 at the end of the barrel-strap, so that on the closing of the revolver the said tip comes upon the shoulder of a notch c' formed in the face 15 of the standing breech c , and is thereby lifted, so as to keep the alinement-stud clear of the rearward channels a^3 in the cylinder, which is thus freed for rotation.

The stud p , which has a straight shoulder 20 p^3 to engage the cylinder-channels a^4 and an inclined or wiper face p^4 , is designed for setting the cylinder in such a position relative to the fixed peg so as to insure its rotation in the proper direction, and in addition to this 25 the said stud p also fills the function of a cylinder-lock for preventing the withdrawal of the cylinder from its support when the revolver is opened, until the push-piece r has been depressed. For this purpose the part 30 of the cylinder that passes under the stud p is provided with the rearward channels a^3 and intermediate of the forward channels a^4 with a series of peripheral curve-bottomed recesses s , which will freely pass the stud as the cylinder rotates, but which when engaged by the said stud dropping therein, as represented in Fig. 5, effectually prevent any movement of the said cylinder longitudinally, so that to release the cylinder for dismounting 35 40 after the revolver is opened the push-piece has to be operated to lift the locking-stud clear of the said recesses s .

In the ordinary revolver (illustrated in Figs. 6 to 11) the device for locking and alining the 45 cylinder a to the barrel b' consists of a single rocking spring-limb p' , located within a sinking b^2 in the under side of the barrel-strap b and pivoted at p^2 at a point between the forward end and its middle, while the tip p^3 of 50 the extreme rear end extends into the eye b^3 at the end of the said barrel-strap and is adapted to be engaged by the shoulder of a notch c' cut in the face of the standing breech c . The forward end p^4 of the said limb is 55 acted upon by a push-piece r , working through and projecting above a hole in the barrel-strap, while rearward of the joint p^2 is a depending tooth p , adapted to engage (when the weapon is opened) with one or other of a series of small notches s , formed around the periphery of the cylinder in radial alinement with the axis of the cylinder-chambers a' and whereby the cylinder is locked to the barrel with one of its chambers in proper alinement. 60 65 The spring p^5 , which automatically takes the tooth p into engagement when the tip end of the lever is freed from the notch in the stand-

ing breech, is located between the top of the lever and the roof of the sinking in the strap.

The cylinder is freed or disengaged from 70 the lock for rotation when the revolver is closed by the shouldered notch of the breech impinging against the extending end of the spring-lever and lifting the tooth out of the notch. When closed, a chamber of the cylinder is kept in alinement with the barrel by the usual means provided for that purpose, said means in the present case consisting of a tooth t' , connected with the trigger t and working up through a slot in the frame 80 or body b^4 of the revolver to engage the undermost notch s , which is held in the desired position by the stud p engaging with the topmost notch, it being understood that the said stud p is not lifted clear of the said top notch 85 until the undermost notch has been passed into engagement with the trigger-tooth t' by the act of closing the revolver.

The cylinder may be provided with a series of shouldered lumps or snugs u , arranged, 90 respectively, over the chambers and alinable with the notches, the same being adapted to take into and engage the shoulders of grooves or channels u' u^2 , cut across the under side of the barrel-strap b and the top of the frame 95 or body b^4 , so as to prevent the cylinder being withdrawn from its support when a chamber is in line with the barrel.

To dismount the cylinder after the revolver has been opened, the push-piece r first has to be depressed to rock the spring-limb and lift the tooth p out of engagement with one of the notches s , after which the cylinder is slightly turned, so as to clear the top lump u from the groove u' in the rib, when the said cylinder 100 can then be withdrawn longitudinally from off its support.

Having fully described my invention, what I desire to claim and secure by Letters Patent is—

1. In a revolver, the combination with a removable cylinder provided with recesses, of a cylinder-locking catch adapted to successively engage said recesses, and a hand-operated pusher for acting on said catch to disengage same from the said cylinder-recesses, substantially as set forth.

2. In revolver-firearms; the combination with a removable cylinder having a series of peripheral recesses, of a spring-catch adapted 120 to successively engage said recesses, and a pusher working through the barrel-strap of the revolver and acting upon said catch for the purpose of disengaging the same from the said cylinder-recesses, substantially as herein 125 described and also as set forth.

3. In revolver-firearms; the combination with a cylinder-locking catch; of a cylinder-alinement device, and a means for disengaging both catches simultaneously from the cylinder, substantially as herein described and set forth.

4. In automatic revolver-firearms; the combination with a cylinder having a zigzag race,

5 peripheral recesses alternating with forward channels, of a catch and backward channels, acting both as a cylinder-lock and a direction device, a second catch for retaining the cylinder in alinement with the barrel when the barrel is opened, and a means for simultaneously disengaging both catches from the cylinder, substantially as herein described and also as set forth.

10 5. In revolver-firearms; the combination with a cylinder, having peripheral recesses, of a combined cylinder lock and alinement device, which automatically engages with one of the said recesses of the cylinder when the revolver is opened, but is lifted out of such engagement when the revolver is closed, the same also being provided with a pusher-re-

leasing means arranged and acting substantially in the manner herein described.

6. In revolver-firearms; the combination with a cylinder locking and alinement device, of a cylinder provided with a series of separated lumps, successively engaging with a recess, sinking or shoulder on the under side of the barrel-strap, for the purpose of preventing the withdrawal of the cylinder, substantially as herein described and set forth.

In testimony whereof I have hereunto set my hand in presence of two subscribing witnesses.
